UNITED STATES PATENT OFFICE.

WILLIAM E. WREAD, OF LOS ANGELES, CALIFORNIA, ASSIGNOR, BY MESNE ASSIGNMENTS, TO MCKINNEY MANUFACTURING COMPANY, OF PITTSBURGH, PENNSYLVANIA, A CORPORATION OF PENNSYLVANIA.

REISSUED

LATCH UNIT.

Application filed August 31, 1925, Serial No. 53,548. Renewed January 4, 1928.

This invention relates to that type of latch unit particularly applicable to the doors of houses, closets, cupboards and similar structures.

5 One object is to provide a novel latch unit having handles on each side of the door to which it is attached and the bolt of which may be retracted by the handle on either side of the door, irrespective of whether the 10 handle on the other side of the door is immovably held or not.

Another object is to provide a latch unit of the character described in which the handles or knobs may be securely fastened 15 to the bolt operating means without the necessity of set screws.

Another object is to provide a novel mounting for the knobs of a door whereby end play of the shaft, to which the knobs are secured, 20 is practically eliminated.

The invention further provides a latch unit with a cross-head at the inner end of the draw bolt and which cross-head may be independently operated from either side of 25 the latch unit to retract the draw bolt.

Objects of my invention are to provide a latch unit, which is simple in construction, inexpensive to manufacture and which may be quickly installed with a minimum amount 30 of labor.

Features of invention reside in the parts and combinations of parts as more fully herein-after described.

Other objects, advantages and features of 35 invention may appear from the accompanying drawings, the subjoined detailed description and the appended claims.

The accompanying drawings illustrate the invention.

40 Figure 1 is a plan view of a latch unit constructed in accordance with this invention, attached to a door a fragment of which is shown. Dotted lines indicate the lock body.

Fig. 2 is an edge view of the same looking 45 from the left of Fig. 1.

Fig. 3 is a side elevation of my latch unit in a door.

Fig. 4 is a sectional view on line x^4 , Fig. 1.

Fig. 5 is a sectional view on line x^5 , Figs. 50 1 and 4.

Fig. 6 is a detail edge view of the latch unit body assembly, detached from the door and co-related parts.

Fig. 7 is a plan view of the assembly shown in Fig. 6.

Fig. 8 is a side elevation of the assembly shown in Figs. 6 and 7.

Fig. 8^a is a perspective view of the latch unit bolt retracting member.

Arrows on the various section lines indicate the direction of sight for the respective views.

My latch unit A comprises a tubular body 1 and end plates 2 that are threaded into or otherwise secured to either end of the body 1, 65 and if desired one plate may thread into the body and the other may be cast integral therewith. Each plate 2 is formed with a tubular extension 3, which extends therefrom, and protrudes from the front or rear 70 face of the door *a* as the case may be.

A draw bolt 4 screws into a hollow sleeve 5 that is slidably mounted on a pin 6 for reciprocal movement in the body 1. The sleeve 5 extends from the body 1 through an opening 7 which also forms a bearing for the sleeve 5.

A crosshead 8 is formed on the inner end of the sleeve 5 and is positioned within the body 1. A tapered latch member 9 is suitably connected to the outer end of the draw bolt. The latch member 9 is adapted to extend from the free edge *b* of the door to which the latch unit is attached and to engage the usual catch plate, well known in the art.

The latch member 9 is slidably mounted in a guide plug 10 which forms a bearing for the outer end of draw bolt. The plug 10 is fitted into the free edge *b* of door *a* as 90 more fully herein-after set forth.

A pin 6 is provided which slidably engages sleeve 5 at one end, the pin 6 having a reduced end 11 that extends through the body 1 and said reduced end is riveted over to securely fix the pin to the body 1. Resilient means in the form of a spring 12 encircling the pin 6 operates between the cross head 8 and the body 1 to normally urge the draw bolt 4 outwardly.

100 Oscillatable means are provided to engage the crosshead and retract the draw bolt 4 and such means comprise retracting members 13 each having a bearing 13' journaled in the extension of plate 2, 3 and having on its inner end within the body 1, a disc 14 and on its

outer end a reduced threaded tip 15 which extends beyond the outer end of the members 13 and is adapted to have a knob 16 of any convenient shape screwed thereon. An arcuate lug 17 is provided on the inner face of the disc 14 and the spring 12 normally holds the crosshead 6 against the ends of said lug 17. The parts are so assembled and related, as shown in Fig. 4, that, when in a state of rest, 10 the plate 8 engages the ends of the lug 17 and holds the disc 14, and associated parts, in symmetrical and balanced position, with the latch 9 extended to full latching position.

Rotation of either knob 16 oscillates the associated member 13 and lug 17 so that either end of said lug, according to the direction of rotation of said knob, will force the crosshead 6 inwardly against the tension of spring 12, as shown in dotted lines in Fig. 4, and thereby slide the draw bar 4 inwardly and retract the latch member 9.

The crosshead 6 may be moved by rotation of one knob irrespective of whether the other knob is held, and may consequently be 25 retracted by rotation of either knob in either direction, at all times. Rotation of either knob, to operate the latch, will not have any turning effect on the other knob, which will remain stationary, and the resistance to rotation will thus be lessened. Upon release 30 of either turned knob, however, and return of the parts to normal position, under the action of spring 6, the disc will engage the lugs 17 on both knobs, ensuring correction of any 35 accidental displacement of the idle knob, and positioning both for further operation.

A cover plate 18 is securely held in position over the tubular body 1 and bore B in which the body is mounted, by a cap 19 that is 40 screwed onto each of the tubular extensions 3. The cap 19 is provided with a shoulder 19' that engages the plate 18 and the tighter cap 19 is screwed onto the extension 3 the tighter plate 18 will be drawn against the 45 door a.

Each cap 19 is formed with a central opening 18' through which the shank c of the knob 16 enters when such knob is screwed home on the threaded tip 15.

To mount the latch unit A in the door a, a transverse bore B of suitable diameter to receive the lock body 1 is made through the door by any suitable bit and brace. A bore C is 50 drilled into the bore B from the free edge b 55 of the door and is of slightly smaller diameter than the guide plug 9 but still large enough to permit the tapered latch member 7 to be freely rotated therein during assembly.

In assembling the latch unit in a door the 60 latch member 9 is detached from the sleeve 5 which is retracted into the lock body 1 thereby permitting such lock body to be inserted into the bore B. The latch member 9 is then threaded into sleeve 5 a sufficient distance to 65 leave a predetermined length of said latch

member protrude from the free edge b of the door a. The guide plug 10 is then driven into the bore C until the outer face of the plug 10 is flush with the free edge of door a. The serrated edges of plug 10 tends to prevent accidental withdrawal of said plug.

The plug 10 prevents rotation of the latch member 9 and also closes the outer end of bore C thereby providing a neat finished appearance.

I claim:

1. A latch unit comprising a body having extensions forming bearing members, a draw bolt extending from said body; two retracting members in said body adjacent said draw bolt and journaled in said bearing members; and means on each of said retracting members adapted to engage and retract said draw bolt, each of said retracting members being independently adapted to retract said draw bolt.

2. A latch unit comprising a body, a draw bolt having a crosshead member reciprocally mounted in said body; yielding means urging said crosshead member in a direction outwardly from said body; a retracting member mounted in said body; means on said retracting member adapted to engage said crosshead to retract said crosshead member against the tension of said spring; guide means on the latch body, forwardly and rearwardly of the crosshead, with which the crosshead has slideable engagement.

3. A latch unit comprising a body, a draw bolt comprising a crosshead member reciprocally mounted in said body, a latch member screwed into said crosshead member; yielding means urging said crosshead member outwardly from said body; retracting members rotatably mounted in said body and comprising a disk, a lug on said disk adapted to engage said crosshead and retract said draw bolt in either direction of rotation; and a knob mounted on said retracting member.

4. A latch unit comprising a tubular body; tubular extensions on said body; a retracting member journaled in said tubular extensions; a knob on said retracting member; a guide pin extending into said body; a draw bolt having a crosshead member, said draw bolt being reciprocally mounted on said pin; a spring between said body and said head to normally urge the draw bolt outwardly from said body.

5. In combination with a door or the like having a bore therein and a second bore communicating with said first named bore; a latch unit comprising a body positioned in said first named bore; tubular extensions on said body protruding from both sides of said door; a draw bolt extending from said body through said second bore; retracting means mounted in said tubular extensions; means operatively connecting said retracting means and said draw bolt; a knob secured to said retracting means; cover plates covering said

first named bore; and caps screwed on said extensions to draw said plates against said door.

6. In combination with a door or the like having a bore therein and a second bore communicating with said first named bore; a latch unit comprising a body positioned in said first named bore; tubular extensions on said body protruding from the sides of said door; a draw bolt comprising a crosshead member in said body, said draw bolt extending through said second bore; a latch member having a threaded shank screwed into said crosshead member; a plug in said second bore to close the outer end thereof; retracting means mounted in said tubular extensions; means operatively connecting said crosshead member and said retracting means; a knob secured to said retracting means; a plate covering said first named bore on each side thereof; and a cap screwed on said extension against said plate to retain said body and plates in position.

7. A latch unit comprising a body, a draw bolt comprising a crosshead member reciprocally mounted in said body; a sleeve extending from said crosshead; a latch member secured to said sleeve; a pin fixed to said body and extending into said sleeve; a spring surrounding said pin and engaging said head to urge the crosshead member outwardly; a retracting member comprising a disk; an arcuate lug on said disk against which said crosshead normally rests; and means to rotate said disk to retract said crosshead member and draw bolt.

8. A latch unit comprising a body, a draw bolt comprising a crosshead member reciprocally mounted in said body, a sleeve extending from said crosshead; a latch member secured to said sleeve; a pin fixed to said body and extending into said sleeve; a spring surrounding said pin and engaging said head to urge the crosshead member outwardly; a tubular extension on said body; a retracting member journaled in said extension; a knob secured to said retracting member; a disk on said retracting member; a lug on said disk against which said crosshead normally rests, said lug being adapted to retract said head when said knob is rotated; other retracting means comprising a disk, a lug on said disk adapted to engage said head, said other retracting means being operable irrespective of said first-named retracting means.

9. A latch unit comprising a body, a latch carrier extending through one wall of the body, a guide member on the rear wall of said body for slidably supporting the inner end of the carrier, a cross head on the carrier disposed within the latch body, and means for yieldingly urging said cross head in an outward direction.

10. A latch unit comprising a body, a latch carrier extending through one wall of the

body, a guide member on the rear wall of said body for slidably supporting the inner end of the carrier, a cross head on the carrier disposed within the latch body, means for yieldingly urging said cross head in an outward direction, and a roll back member engaging said head to each side of the longitudinal center line of said carrier member.

11. A latch unit comprising a body, extensions on said body, retracting devices journaled in said extensions and positioning plates having screw-threaded adjustment with respect to said extensions, the said plates being adapted to engage the faces of a door containing the unit and serving as means for positioning the lock body in a desired vertical plane within a door.

12. A latch unit comprising a body, a cross head member mounted for reciprocable movement in said body, a latch member having a shank portion connected to and adjustable with respect to said cross head member on its longitudinal axis, retracting means disposed forwardly of said cross head for withdrawing the latch, and yieldable means disposed rearwardly of said cross head for urging the same forwardly.

13. A latch unit comprising a housing having an opening through one of its sides, a bolt carrier, a bolt having screw threaded connection with the outer end of said carrier, and a spring engaging a rear surface of the carrier to urge the same outwardly, the wall of said opening serving to guide the carrier and bolt during reciprocable movements thereof.

14. A bolt operating mechanism comprising in combination with a housing having a lateral orifice; a bolt carrier comprising a member operable in the housing, and provided with a lateral extension operable through the orifice, and adapted for connection with a latch bolt; and means to move the carrier to operate the extension through the orifice.

15. A bolt operating mechanism comprising in combination with a housing having a lateral orifice; a bolt carrier comprising a member operable in the housing, and provided with a lateral extension operable through the orifice; means to move the carrier to operate the extension through the orifice, and a bolt shank adjustably threaded in the extension.

16. A bolt operating mechanism comprising a housing having a lateral orifice; a bolt carrier comprising a member operable in the housing and an extension operable through the orifice; a spring to hold the carrier toward the side of the housing having the orifice, and means to retract the carrier.

17. The combination with a housing having a lateral orifice, of a bolt carrier having a bore and mounted in the housing and provided with an extension in said orifice: a coil

- spring to hold the carrier toward that side of the housing provided with the orifice; said extension having a bore; a guide pin fixed in the housing and extending through the coil 5 spring and into the bore; and means to retract the carrier and extension against the force of the spring.
18. The combination with a housing having a lateral orifice, and having a journal bearing in one end; of a carrier mounted in the housing and provided with a bore, and with an extension, operable in said orifice; a spring to hold the carrier toward the side of the housing provided with the orifice; a 10 pin fixed in the housing and extending into the bore; a cam to operate the carrier, and a spindle carrying the cam and journaled in one of the bearings and adapted to operate the carrier to retract the carrier against the 15 pressure of the spring.
19. A bolt operating mechanism comprising a housing having a journal bearing at one end and an orifice at one side, a bolt carrier provided with a flat face and having an 20 extension operable through the orifice, means to yieldingly hold the carrier toward the orifice; a plate having a spindle journaled in the bearing and a cam to retract the carrier.
20. Bolt operating mechanism comprising a housing having a chamber with a lateral orifice, a flat inside end wall and a journal bearing opening into the chamber through said end wall; a bolt carrier mounted in the chamber and having an extension in the lateral orifice; means to hold the carrier toward the orifice; a disk fitted against the flat end wall and provided with a spindle in said bearing and with a cam to operate the carrier.
21. A latch housing comprising a shell and two threaded hubs forming journal bearings, facing plates on said threaded hubs and nuts on said hubs to hold said facing plates against a closure when the shell is mounted in such closure.
22. The combination with a closure, of a latch housing comprising a shell having an open end and a transversely extending way in the side for a bolt connection; a detachable end piece for the open end of said shell, the other end of said shell and said end piece being provided with hubs forming journal bearings for spindles for the operation of a bolt-operating mechanism within the chamber, and means for adjusting the position of the shell within the closure.
23. The combination with a closure, of a latch housing comprising a shell having an open end and a transversely extending way in the side for a bolt connection; a detachable end piece for the open end of said shell, the shell and end piece being provided with journal bearings and nuts on said hub adapted for adjusting the position of the shell within the closure.
24. The combination with a closure, of a housing comprising a shell having an open end and a transversely way extending in the side for a bolt connection, a detachable end piece for the open end of said shell, hubs formed on said shell and end piece and nuts on said hubs adapted for adjusting the position of the shell in the closure.
25. A latch unit comprising a body formed to lie within an opening through a door and between the outer planes of the door, and having an extension of reduced diameter, a latch-operating spindle journaled in said extension, a face plate at each side of the door, and means for connecting each of said plates to the housing, for adjustment transversely of the door.
26. A latch unit comprising a body portion, a latch-carrying member supported thereby, a latch member, a connecting device rigidly connected to one of said members and adjustably connected to the other member, and means engaging the carrying member for yieldably urging said members outwardly.
27. Latch structure comprising a body portion, a latch-carrying member supported and guided thereby, a latch member having its inner end connected to the carrying member, and means independent of and removed from the body portion, for supporting and guiding the outer end of the latch member.
28. A latch unit comprising a body-portion, bearing members at substantially opposite points on said body-portion, a draw-bolt reciprocable relative to said body-portion, and disposed substantially at right angles to said bearing members, a plurality of draw-bolt operating devices any one of which is operable independently to actuate said draw-bolt, and means exterior of the latch unit support to operate said devices.
29. A latch-unit comprising a body-portion, bearing members extending axially from said body-portion at opposite sides, a draw-bolt reciprocably mounted in said body-portion at substantially right angles to said bearing members, a plurality of draw-bolt operating devices any one of which is operable independently to actuate said draw-bolt, and means exterior of and on opposite sides of the door latch unit support to operate said devices.
30. A latch unit comprising a body-portion having bearing members at opposite sides, a reciprocable draw-bolt mounted in said body-portion at substantially right angles to said bearing members, independently operable draw bolt actuating devices traversing said bearing members, operating connections between said devices and said draw-bolt, and exteriorly disposed means for moving said draw-bolt actuating devices.
31. A latch unit comprising a body-portion having bearing members at opposite

sides, a reciprocable spring-projected draw-bolt mounted in said body-portion at substantially right angles to said bearing members, independently operable draw-bolt retracting devices traversing said bearing members, operating connections between said devices and said draw-bolt, and exteriorly disposed means for moving said draw-bolt retracting devices.

32. A latch unit comprising a body-portion having bearing members at opposite sides, a reciprocable spring-projected longitudinally adjustable draw-bolt mounted in said body-portion at substantially right angles to said bearing members, independently operable draw-bolt retracting devices traversing said bearing members, operating connections between said devices and said draw-bolt, and exteriorly disposed means for moving said draw-bolt retracting devices.

33. A latch unit comprising a body-portion having bearing members at opposite sides, a spring-projected draw-bolt mounted in said body-portion at substantially right angles to said bearing members, draw-bolt guiding means; independently operable draw-bolt actuating devices traversing said bearing members, operating connections between said devices and said draw-bolt, and exteriorly disposed means for moving said draw-bolt actuating devices.

34. A latch unit comprising a body-portion having bearing members at opposite sides, a spring-projected draw-bolt mounted in said body-portion at substantially right angles to said bearing members, draw-bolt guiding means within said body-portion; independently operable draw-bolt actuating devices traversing said bearing members, operating connections between said devices and said draw-bolt, and exteriorly disposed means for moving said drawbolt.

35. The combination with a support having a substantially T-shaped socket, of a latch unit comprising a body-portion mounted in the top bore of the T-shaped socket, a draw-bolt reciprocable in the leg bore of the socket, a plurality of independently operable draw-bolt actuating devices, operating connections between said devices and said draw-bolt, and means disposed exteriorly of the support to move said actuating devices.

36. The combination with a support having a substantially T-shaped socket, of a latch unit comprising a substantially cylindrical body-portion mounted in the top bore of the T-shaped socket, a longitudinally adjustable draw-bolt reciprocable in the leg bore of the socket, a plurality of independently operable draw-bolt actuating devices, operating connections between said devices and said draw-bolt, and means disposed exteriorly of the support to move said actuating devices.

37. The combination with a support having a substantially T-shaped socket, of a latch-unit comprising a cylindrical body-portion mounted in the top bore of the T-shaped socket, a spring-projected draw-bolt reciprocable in the leg bore of the socket, a plurality of independently operable draw-bolt actuating devices, operating connections between said devices and said draw-bolt, and means disposed exteriorly of the support to move said actuating devices.

38. The combination with a support having a substantially T-shaped socket, of a latch-unit comprising a cylindrical body-portion mounted in the top bore of the T-shaped socket, a spring-projected draw-bolt reciprocable in the leg bore of the socket, and retractable entirely within said body-portion, independently operable draw-bolt actuating devices, operating connections between said devices and said draw-bolt, and means disposed exteriorly of the support to move said actuating devices.

39. The combination with a support having a substantially T-shaped socket, of a latch-unit comprising a body-portion mounted in the top bore of the T-shaped socket, means for securing said body portion in the bore, a draw-bolt reciprocable in said body-portion and extending into the leg bore of the socket, means for supporting the outer end of said draw-bolt, and independent draw-bolt operating means in said body-portion and operable exteriorly from either side of said support.

In testimony whereof, I have hereunto set my hand at Los Angeles, California, this 21st day of August, 1925.

WILLIAM E. WREAD.
